UNITED STATES PATENT OFFICE

GEORGE A. RICHARD, OF HILL CITY, MINNESOTA

HEEL PAD

Application filed January 27, 1930. Serial No. 423,698.

This invention relates to heel pads and has special reference to one particularly adapted for use in the heel of the ordinary shoe, the principal object being to provide simple means for the furtherance of comfort of the user.

Another object is to provide convenient means for the elevation of the heel of the foot within the shoe in permitting the foot to assume the most natural position when the shoe engages the ground.

Still other objects and advantages of the invention will appear in the further description thereof.

15 Referring now to the accompanying drawings, forming part of this application, and wherein like reference characters indicate like parts;

Figure 1 is a top plan view of one of the 20 completely assembled pads embodying the invention;

Figure 2 is a vertical section on the line 2—2 of Figure 1;

25 Figure 3 is a section on the line 3—3 of Fig. 1;

Figure 4 is a plan view of the inside of the heel portion of a shoe with one of the pads installed therein, and as it would appear after some considerable wear.

30 The pad is of fabricated construction and comprises the bottom or foundation layer 1, preferably of sheepskin leather, and an upper layer or cover 2, of like leather, the latter being materially longer than the bottom layer, such additional length being upon the forward end thereof, as the two layers are intended to register throughout except at the forward edge.

35 These members are sewed together or 40 stitched longitudinally a portion of the straight sides thereof as at 3 resulting in both ends being open, forming a receptacle for the pad or cushion member 4 which is of sponge rubber and insertable within the receptacle; it being formed the general shape of the interior thereof and readily removable when desired through the open rear end. This pad 4 is novel in that the forward or narrower end thereof is bifurcated 45 a considerable distance inwardly of the pad,

and the upper edges of said bifurcated portion and inner termini thereof are chamfered or beveled as indicated at 5. The bifurcation of the end of the pad is accomplished by the V-shaped notch 6 forming 55 centering means for the heel of the wearer, as the bottom of the forward portion of the heel is naturally arcuate in shape transversely and consequently it will tend to center within this V-shaped recess, the same being 60 found to function admirably in keeping the heel pad in proper position within the heel of the shoe.

This centering feature of the pad is particularly essential in that the completely assembled pad is preferably made considerably smaller in width than the width of the heel portion of the shoe in which it is used.

65 It is well known that a shield pad or other piece of leather installed within the heel of a shoe has a marked tendency to creep and must be either glued or fastened in different places to maintain its proper position, whereas my improved pad can be made considerably smaller than the area 70 within the heel and held in position with but a single tack, this being due to the automatic centering element just described.

75 The principal marked advantage of the pad being made smaller than the area of 80 the heel, is to permit ready circulation of air in proper ventilation in and about the heel of the wearer, and it is found in practice that after long use both walls of the pad as well as the resilient member itself remain 85 perfectly dry and comfortable to the wearer.

85 The base member 1 of the pad extends considerably beyond the forward end of the cushion member 4 providing ample room 90 for the single tack 7 for holding same in position; this tack occurring just forwardly of the V-shaped cutaway portion of the resilient member is amply protected against interference in any way with the wearer, and the cover member extending still further beyond both the resilient member and bottom member 1 provides a loose but adequate wearing and shielding surface. Furthermore it is found by the use of such a pad 95 100

that the foot becomes somewhat elevated just forwardly of the heel upon either side thereof, permitting of longitudinal air channels as it were on either side of the pad, and this to such an extent that frequently the edges of the insole indicated at 8 turn up slightly as shown at 9, partially filling said space and further tending to properly center the pad, and thus providing a heel-centering pad which is susceptible to variations corresponding to the characteristics of the wearer's feet, it being essential that the major portion of the thrust of the wearer's weight occur at the center of the heel.

Having thus described my invention, what I claim and desire to secure by Letters Patent, is:

1. A heel pad for shoes of a shape similar to that of the interior of the heel of the shoe though materially narrower throughout the forward portion thereof, said narrower portion having straight converging sides, said pad comprising two similarly shaped flexible members being stitched together only longitudinally of said straight sides resulting in both ends being open, and a resilient pad insertable intermediate of the two converging members.

2. A heel pad for shoes of a shape similar to that of the interior of the heel of the shoe though materially narrower throughout the forward portion thereof, said narrower portion having straight converging sides, said pad comprising two similarly shaped flexible members being stitched together only longitudinally of said straight sides, resulting in both ends being open, a resilient pad insertable intermediate of the two converging members, said pad being provided with heel-centering means for the purpose described.

In testimony whereof I affix my signature.
GEORGE A. RICHARD.
